KNIFE OR THE LIKE

Richard S. Latham, Chicago, Ill., assignor to American Home Products Corporation, New York, N.Y., a corporation of Delaware

Filed Dec. 3, 1965, Ser. No. 34

Term of patent 14 years

(Cl. D95—3)

FIG. 1 is a bottom edge view of a knife or the like showing my new design;

FIG. 2 is a plan view thereof;

FIG. 3 is a top edge view thereof; and

FIG. 4 is an enlarged transverse section taken on line 4—4 of FIG. 1.

The characteristic features of the present design reside in the portions shown in full lines wherein the handleward end of the blade is thickened to provide a bolster forming a smooth continuation of the longitudinally extending outer surfaces of the handle, said blade having the handleward end of its cutting edge in downwardly and forwardly offset relation to said bolster, said bolster having a first branch forming an elongated downward and forward extension of the bolster which is of progressively reduced thickness in the direction of the cutting edge of the blade and terminates in a lower extremity coincident with the handleward end of the cutting edge of the blade, and having a second branch forming an elongated extension bordering the back edge of the handleward end portion of the blade and of progressively reduced thickness in a direction away from the handle and a pair of straight

lines joined in acute angular relation by a rounded corner line to define those peripheral limits of said branches which face in the direction of the area of the blade in forward relation to said bolster.

I claim:

The ornamental design for a knife or the like, substantially as shown and described.
